(57) **CLAIM**

The ornamental design for a UHF antenna, as shown and described.

DESCRIPTION

FIG. 1 is a front perspective view of the design for the UHF antenna having a number of environmental features, namely, a pair of vertical antennas, a pair of joints, a support stem, and a base;

FIG. 2 is a side perspective view of the design for the UHF antenna of FIG. 1, further illustrating the environmental pair of vertical antennas, pair of joints, support stem, and base introduced in FIG. 1;

FIG. 3 is a front view of the design for the UHF antenna of FIG. 1, further illustrating the environmental pair of vertical antennas, pair of joints, support stem, and base introduced in FIG. 1; and,

FIG. 4 is a rear view of the design for the UHF antenna of FIG. 1, further illustrating the environmental pair of vertical antennas, pair of joints, support stem, and base introduced in FIG. 1.

In the above listed figures, the broken lines showing of a pair of vertical antennas, a pair of joints, a support system, and a base are for illustrative purposes only and form no part of the claimed design.

The broken line showing of a pair of vertical antennas, a pair of joints, a support stem, and a base is for illustrative purposes only and forms no part of the claimed design.
